UNITED STATES PATENT OFFICE.

GEORGE W. ANDERSON, OF LADOGA, INDIANA.

RAKE.

SPECIFICATION forming part of Letters Patent No. 789,831, dated May 16, 1905.

Application filed November 18, 1904. Serial No. 233,266.

To all whom it may concern:

Be it known that I, GEORGE W. ANDERSON, a citizen of the United States, residing at La-
doga, in the county of Montgomery and State
5 of Indiana, have invented certain new and
useful Improvements in Rakes, of which the
following is a specification.

The object of my invention is to produce a
rake structure having a cross-bar formed of
sheet metal and teeth formed of wire, the
construction being such that the teeth may
be single and yet may be prevented from any
turning upon their axes.

The accompanying drawings illustrate my
5 invention.

Figure 1 is a perspective view of a portion
of a rake embodying my invention; Fig. 2, a
transverse section; Fig. 3, longitudinal sec-
tions, and Figs. 4 and 5 are sectional details
o of a modified form.

In the drawings, 10 indicates a sheet of
metal which is bent into a tubular form and
provided on the sides of the tubes with
perforations 11. The back of the tube or cross-
5 bar thus formed is provided in alinement with
each pair of perforations 11 with a dimple 12.

Tooth 13, which is formed of a piece of
wire, is first passed through a pair of perfor-
ations 11 and then kinked in its middle, as at
o 13', said kink extending into the dimple 12.
In practice the dimple 12 and kink 13' will
be formed simultaneously in the following
manner: The body 10 is partially formed, the
front lips 10' extending at right angles to the
5 back. The tooth 13 is then passed through
the pair of perforations 11 and the parts then
placed under a plunger and over a die mem-
ber which is provided with a depression of
the form of the dimple 12. The plunger de-
o scends and simultaneously forms the kink 13'
and the dimple 12.

I am aware that in rakes of this character
it has been heretofore proposed to provide
the tubular head with a longitudinal groove
formed in the back into which the wire teeth
45 are kinked; but this construction serves
merely to prevent longitudinal withdrawal of
the teeth and does not prevent turning of
the teeth, and it has therefore been necessary
to make the teeth double. In the present 50
construction by making use of a dimple op-
posite each tooth the tooth can neither be
withdrawn longitudinally nor turned axially.

In Figs. 4 and 5 I have shown a modifica-
tion in which the bar 10 is provided in its 55
face with a plurality of narrow slots 12',
which take the place of the dimples 12, and
the kinked portion 13' of the tooth is forced
into the alined slot 12'.

I claim as my invention—

1. In a rake, the combination of a cross-
head having a pair of tooth-receiving perfora-
tions and an alined receptacle for an inter-
mediate kinked portion of the tooth, and a
tooth passed through said perforations and 65
having an intermediate portion between the
perforations kinked into said receptacle.

2. In a rake, the combination of a cross-
head having a pair of tooth-receiving perfora-
tions, and a dimple formed in alinement 70
therewith, and a tooth passed through said
perforations and having a portion between
said perforations kinked into said dimple.

In witness whereof I have hereunto set my
hand and seal, at Ladoga, Indiana, this 14th 75
day of November, A. D. 1904.

GEORGE W. ANDERSON. [L. S.]
